UNITED STATES PATENT OFFICE.

JOSEPH L. WALKER, OF BATON ROUGE, LOUISIANA, ASSIGNOR TO THE K-D BARREL & HAMPER CO., OF BATON ROUGE, LOUISIANA.

BARREL-MAKING MACHINE.

Application filed October 21, 1922. Serial No. 596,035.

To all whom it may concern:

Be it known that I, JOSEPH L. WALKER, a citizen of the United States, residing at Baton Rouge, in the parish of East Baton Rouge and State of Louisiana, have invented a new and useful Barrel-Making Machine, of which the following is a specification.

This invention relates to a machine for making drums or barrels of that type shown, for example, in Patents No. 1,430,419 and No. 1,430,420 issued to me on September 26, 1922.

One of the objects of the present invention is to provide means whereby the hoop strips and the staves of the drum or barrel can be properly assembled and fed to a former, there being means combined with the former for nailing or stitching the parts together.

Another object is to combine with the former a means for properly positioning liner hoops and a head within the formed drum or barrel body where they can be fastened by means provided for that purpose.

Another object is to provide operating mechanism which will automatically be thrown out of gear when the assembled parts of the barrel are brought into operative position relative to the nailing or stitching mechanism.

A further object is to provide means under the control of the operator for coupling the nailing mechanism to the driving mechanism whereby the former, with the assembled parts thereon, will be operated with a step by step movement during the fastening operation.

Another object is to provide means for automatically stopping the rotation of the former after it has been brought to its initial position and for reversing the rotation of the former upon the completion of the formation of the barrel.

With the foregoing and other objects in view which will appear as the description proceeds, the invention consists of certain novel details of construction and combinations of parts which will be hereinafter more fully described and pointed out in the claims.

In the accompanying drawings the preferred form of the invention has been shown.

In said drawings—

Figure 1 is a plan view of the machine.
Figure 2 is an end elevation thereof.

Figure 3 is an elevation of the opposite end of the machine.

Figure 4 is a section on line 4—4 Figure 1.
Figure 5 is a section on line 5—5 Figure 1.

Figure 6 is a plan view of the feed carriage.

Figure 7 is an end elevation of a portion of the carriage.

Figure 8 is an enlarged view partly in side elevation and partly in section of one end portion of the carriage.

Figure 9 is a perspective view of one of the stave engaging members on the carriage.

Figure 10 is a view partly in elevation and partly in section of a portion of the carriage, its track, and its adjusting roller.

Figure 11 is a view partly in section and partly in elevation of the track and carriage and the means for adjusting the same, said view being at right angles to Figure 10.

Figure 12 is an enlarged section on line 12—12 Figure 1.

Figure 13 is a plan view of a portion of the clutch shifting gear, showing one of the cams thereon.

Figure 14 is an enlarged section through the head applying portion of the former.

Figure 15 is a plan view of the assembled hoop strips and staves prior to being shaped into a barrel or drum.

Figure 16 is a side elevation showing the staves and hoop strips assembled with the carriage a portion being broken away.

Figure 17 is a section through a portion of the head applying part of the apparatus, showing a finger in normal position.

Referring to the figures by characters of reference, 1, 2 and 3 designate upstanding frame members connected at their lower ends by front and back longitudinal beams

4 and also by a beam 5 fastened on brackets 6 extending forwardly from the upper portions of the frame members. The frame members 1 and 2 are connected by a bar 7 which bridges the space between them and has downwardly extending ends 8 fastened to the respective frame members.

In these two frame members 1 and 2 is journaled the shaft 9 of the barrel former. This shaft extends across the space between the frame

110

members 2 and 3 and has secured to it substantially semi-circular segmental sections 10 formed with collars 11 extending around the shaft. To each section 10 is connected 5 an arcuate section 12 by means of a hinge indicated generally at 13. Each section 12 has a recess 14 in its periphery for the reception of a clamping plate 15 extending from a shank 16. The shank is mounted in 10 a guide 17 carried by the section 12 and said shank is connected by a stem 18 to a bracket 19 fastened to collar 11. A spring 20 is mounted on stem 18 and thrusts against the guide 17 so as to hold the section 12 normally pressed outwardly with the plate 15 seated in recess 14.

A rod 21 is extended transversely through the sections 10 and has an arm 22 at one end whereby it can be rotated readily by the 20 operator. Secured to the rod or shaft 21 close to each of the sections 10 is an eccentric 23 on which is mounted a loop 24 provided at one end of a rod 25. The rod is pivotally connected at 26 to the free end 25 portion of the section 12 adjacent thereto. Thus it will be seen that by rotating the rod or shaft 21 in one direction all of the eccentrics will simultaneously shift the rods 25 so as to swing the sections 12 away from the 30 sections 10, thus to expand the barrel former made up of the sections and at the same time seat the clamping plates 15 within the recesses 14. By rotating the shaft or rod 21 in the opposite direction the sections 12 will 35 be pulled inwardly toward the sections 10, thus withdrawing from the clamping plates 15 and contracting the barrel former.

The frame member 3 has an unobstructed 40 opening 27 therein the diameter of which is slightly greater than the diameter of the barrel to be formed. The former sections 10 and 12 nearest this frame member 3 are formed in their outer edges or peripheries with grooves 28 adapted to receive a liner 45 hoop as hereinafter pointed out. The clamping plate 15' carried by this portion of the former is so shaped as to extend laterally from its shank 16' for the purpose of engaging a hoop strip located to one side of the 50 shank. (See Figure 14).

Brackets 29 are extended rearwardly from the frame members 2 and 3 and support a rod 30 on which are mounted blocks 30' carrying presser rollers 31 for engaging the 55 hoop strips of a barrel while being bent about the former. These presser rollers and the means for mounting them do not, in themselves, constitute any part of the present invention but are already disclosed in my 60 Patent 1,437,575.

Connecting the members 2 and 3 above the presser rolls 31 is a bar 32 on which are mounted separate nailing tools indicated generally at 33 and which can be of any 65 well known magazine type. One of these

tools is provided for each hoop strip of the barrel to be formed and all of the nailing tools are adapted to be actuated simultaneously by eccentrics 34 mounted on an operating shaft 35. As the nailing tools can be of any standard make it is not deemed necessary to illustrate them in detail.

Mounted in the frame members 2 and 3 are bearings 36 yieldingly supported by 70 springs 37 and engaging a shaft 38 adapted to be rotated in any suitable manner, as by means of a crank arm 39. This shaft is provided, between its ends, with an eccentric portion 40 adapted to support angle rails 41 which constitute the track of a feed carriage. These rails are pivotally supported near 75 their outer or front ends as shown at 42 and extend over the eccentric portion 40 and through and beyond the space between the frame members 2 and 3.

Mounted on and concentric with the eccentric portion of the shaft 38 is a roller 43. This roller is located substantially in vertical alignment with the shaft 9 and projects between the rails 41. It is adapted to engage and support longitudinal strips 44 mounted on and secured adjustably to end strips 45. These end strips have longitudinal slots 46 for the reception of bolts 47 used for fastening the strips together. Side strips 48 are fixedly secured to the 80 ends of the strips 45 and all of the strips cooperate to form the body of a feed carriage. Rollers 49 are connected to and support the ends of the strips 45 and are adapted to travel along the angle rails 41 and past the ends of the eccentrically mounted roller 43.

Certain of the strips 44 constitute stave supports and have strips, preferably of wood, secured longitudinally thereon as 85 shown at 50. On each of these strips is secured a longitudinal series of stave holders. Each holder, as shown in Figure 9, includes an attaching base 51, and upwardly and forwardly inclined arm 52, a tongue 53 extending downwardly from the upper end of the arm, and a lug 54 struck upwardly from the tongue. These stave holding devices are spaced apart distances 90 slightly less than the width of the staves so that, as shown in the drawings the beveled lower side of each stave S will rest upon the tongues 53 of two corresponding supports while the opposite edge of the stave will rest on two of the lugs 54 so as to lap the supported edge of the next adjoining stave. All of the staves are extended transversely of the carriage and across all of the strips 44.

Those strips 44 not provided with stave 95 engaging or holding devices have blocks 55 thereon for supporting longitudinally channeled strips 56 parallel with the strips 50 and each adapted to hold a hoop strip 100

H. These hoop strips, when placed on the carriage are arranged with one end projecting beyond the staves and toward the rear end of the carriage while the other end of each hoop strip terminates inwardly from the front edge of the front or first stave on the carriage. These relative positions of the staves and strips have been shown in Figure 15, which is a view looking down on the assembled staves and hoops approximately as they appear when on the carriage.

Mounted on the rear or outer end of the carriage close to the ends of the channeled strips 56 are standards 57 on which are pivotally mounted clamping levers 58 having springs 59 for forcing the levers downwardly onto the adjoining ends of the hoop strips H. A transverse tripping rod 60 connects the frame members 2 and 3 and is in the path of the levers 58 so that when the carriage reaches the upper limit of its movement the levers will come against rod 60 and be shifted so as to release the hoop strips engaged thereby.

It is to be understood that the eccentric 40 supports the rails 41 and the roller 43 supports the carriage strips 44. Thus when shaft 38 is rotated the rails 41 and the carriage will be raised or lowered in unison relative to the shaft 9, so as to cause the hoop strips to be properly fed to the former.

Journalized in the frame members 1 and 2 is the main drive shaft 61 adapted to be driven by a belt pulley 62 and having gears 63 and 64 secured thereto so as to rotate therewith. Gear 64 meshes with a gear 65 loosely mounted on the shaft 35 of the nailing tools. This gear has a clutch member 66 and another clutch member 67 is feathered on shaft 35 and is adapted to be shifted by a hand lever 68 fulcrumed on a bracket 69 extending from the frame member 2. An eccentric 70 is secured to and rotates with shaft 35 and is adapted to transmit motion through a rod 71 to a crank arm 72 having a pawl 73 pivotally connected to it. A handle 74 extends from the pawl so that it can be easily moved into or out of engagement with a ratchet wheel 75 secured to one end of the shaft 9. Thus it will be seen that when shaft 35 is rotating the nailing tools 33 will be operated and the pawl 73 will be shifted to rotate the ratchet wheel 75, shaft 9, and the barrel former with a step by step movement. In other words the parts are so timed that after each nailing operation the barrel being formed will be given a slight turn so as to bring it into position to receive the next set of nails to be driven thereinto. When lever 68 is located as shown in Figure 1, the nailing apparatus and the ratchet wheel will not operate but by shifting the lever to the right the clutch members 67

and 66 will be brought together and gear 65 will be coupled to shaft 35.

The gear 63 meshes with a gear 76 secured to a shaft 77 and another gear 78 is secured to shaft 77 and meshes with a gear 79 secured to a shaft 80. A clutch member 81 is feathered on shaft 77 and another clutch member 82 is feathered on shaft 80. These two shafts are journaled in a bearing member 83 supported by the bar 7 and an arm 84 is extended between the clutch members 81 and 82. A lever 85 is fulcrumed on the arm 84 and is connected to the clutch members 81 and 82.

Supported by the bar 7 is a bearing member 86 in which are journaled the shafts 77 and 80 provided with gears 89 and 90. Clutch members 91 and 92 rotate with the gears and are supported for engagement by the clutch members 81 and 82 respectively. A large gear 93 is secured to the shaft 9 and meshes with both of the gears 89 and 90. It will be obvious that when the clutch members 81 and 91 are in engagement with each other motion will be transmitted to the gear 93 and shaft 9 through gear 89. When the clutch members 82 and 92 are in engagement with each other motion will be transmitted to gear 93 in the opposite direction through gears 78, 79, and 90. Thus by the mere shifting of lever 85 the shaft 9 can be rotated in either a clockwise or a counter-clockwise direction.

The gear 93 is provided in each side, close to its periphery, with an angular groove 94 and 95 respectively. The inner wall of each groove is inclined inwardly toward the axis of rotation. Each groove is adapted to receive an angular lip 96 projecting from the inner edge portion of a cam block 97 so that the block is thus supported at the side of the gear. The block has an angular arm 98 extending inwardly back of an angular shoulder 99 formed on the gear. A set screw 100 extends through arm 98 and engages the shoulder so as to hold the cam block 97 to the gear. This construction is illustrated in Figure 12. The cam block is preferably triangular as shown in Figure 13.

Supported by the frame members 1 and 2 is a guide rod 101 on which is mounted a slide 102. The lever 85 is extended over this slide and pivotally mounted on the lever at 103 is a handle 104 having a stud 105 projecting from one end thereof. This stud extends into an eye 106 provided at the upper end of a pin 107 slidable within a guide 108 extending from the slide 102. A spring 109 is interposed between lever 85 and handle 104 and serves to hold the pin 107 normally pressed downwardly at one side of gear 93 as shown in Figures 5 and 12. A finger 110 is adjustably secured to the slide 102 and projects downwardly adjacent the other side of gear 93. It will be ap-

parent that when lever 85 is swung in one direction the pin 107 will be brought into the path of the cam block 97 on one side of gear 93 and when the lever is swung in the opposite direction the finger 110 will be brought into the path of the other cam block 97.

Hingedly connected to the frame member 3 as at 111 in Figure 1 is a cross head 112 adapted to extend across the opening 27 in said member and to enter between lugs 113 and to be engaged by a gravity latch 114 or other suitable fastening device. The cross head 112 has a central bearing 115 in which is secured and journaled a stud 116 projecting from the center of a head 117. This head has a peripheral groove 118 corresponding with the groove 28 in the end members 10 and 12. Guides 119 are provided at the periphery of the head and in these guides are mounted slidable holding fingers 120. The fingers are connected to springs 121 which serve to hold the fingers normally projected across the outer open side of the groove 118 and beyond the face of the head 117. Guide brackets 122 are secured on the outer face of the head 117 and are slidably engaged by a cam ring 123 extending between the head 117 and the springs 121. By rotating this ring by means of a handle 124 or the like the springs 121 can be pressed outwardly away from the head 117 so as to withdraw the fingers 120 from their normal positions to the positions shown in Figure 14. The normal position of one of the fingers has been illustrated in Figure 17.

The head of a barrel has been indicated at A and it will be noted that the head engaging faces of the members 10 and 12 in Figure 14 and of the head 117 are provided with small projections or teeth 125 adapted to bite into the head A.

In using this apparatus the shaft 21 is first rotated so as to draw together the members 10 and 12 of the barrel former. The hoop strips H are properly arranged on the channeled strips 56 with their free ends projecting rearwardly and the staves are placed in properly lapped relation on the holders 51-53. Levers 58 are placed in engagement with the back ends of the hoop strips and shaft 38 is rotated so that when the carriage is moved upwardly along the inclined track the front ends of the hoop strips will be brought to position within the recesses 14. Shaft 21 is then rotated to shift the members 12 of the formers outwardly to clamp the ends of the hoop strips against the plates 15, and to grip the front edge of the first stave.

A barrel head of proper dimensions is next placed between the projecting fingers 120 on head 117 so that the head will be properly supported by and between the fin-

gers. A liner hoop L is also placed in the groove 118 back of the engaged barrel head A. Another liner hoop L' is placed in the groove 28. Head 117 is now swung to position so that cross head 112 can be fastened with the latch 114. This will cause the head A to be clamped between head 117 and the end members 10 and 12 of the former. After the parts have thus been positioned the ring 123 can be rotated and the fingers 120 withdrawn from across head A and liner hoop L.

The operator now shifts lever 85 by means of handle 104 so as to couple the clutch members 81 and 91. This will cause the shaft 9 and the barrel former members to rotate so as to gradually wrap or bend the hoop strips and the staves upon the members 10 and 12. As the clamping plates 15 pull on the hoop strips H said strips will in turn pull upon the carriage and cause the staves to be pressed tightly against the members 10 and 12 by the hoop strips.

The parts are so timed that when the advancing edge portion of the first stave arrives in position in line with the nailing tools one of the cam blocks 97 on gear 93 will come against pin 107 and shift it laterally so as to return lever 85 and the clutch member 81 to neutral position. Thus the feeding of the stock will stop automatically.

The operator now shifts lever 68 so as to couple gear 65 to shaft 35. Thus the nailing tools will be operated and the barrel forming members 10 and 12 with their shaft 9 will be rotated intermittently as before explained. This will result in the nailing together of the hoop members and the staves and by mounting two nailing tools at the bottom end of the barrel being formed the nails will not only secure the end hoop strips to the staves but will also enter the liner hoops L and L' and fasten them to the staves.

The nailing operation will continue until the hoop strips have been passed throughout their lengths under the nailing tools at which time the further operation of the machine can be stopped by returning lever 68 to its normal position. The operator can now shift lever 85 so as to couple clutch members 82 and 92 whereupon the rotation of shaft 9 will be reversed. The parts are so timed that when the clamping plates 15 arrive at their normal positions or points of starting one of the cam blocks 97 will come against the finger 110 and shift lever 85 to its neutral position, thus stopping the further rotation of the shaft 9. Head 117 can be swung away from the formed barrel, leaving the barrel head A in position between the liner hoops L and L'. Shaft 21 is then rotated to contract the barrel former. This will allow the completed barrel to be withdrawn from the former

through opening 27 in frame member 3. The apparatus is now ready to repeat the operation before described.

It might be stated that when the carriage 5 is drawn to the upper limit of its movement by the hoop strips being wrapped about the former, lever 58 will come against rod 60 so as to release the carriage and allow it to gravitate back to its normal position ready 10 to be again supplied with stock. By having the shiftable pin 107 the lever 85 can be released from its actuating cam block 97 should it be desired to continue the rotation of the barrel former in the direction from 15 which it has started. The pawl 73 is to be disengaged from the ratchet wheel by handle 74 whenever the shaft 9 is driven through the gears 89 or 90.

What is claimed is:

20 1. In a barrel making machine a former, a carriage, means cooperating with the former for gripping one end of a hoop strip, means on the carriage for gripping the other end of the hoop strip, means for rotating the former to wrap the hoop strip thereon and actuate the carriage, and means for automatically releasing the hoop strip from the carriage.

25 2. In a barrel making machine a former, a track leading to the former, a carriage supported by the track, separate means cooperating with the former and carriage for gripping opposite ends respectively of the stock on the carriage, means for rotating the former to pull through the stock upon the carriage and move the carriage upon the track, and means for automatically releasing the stock from the carriage, said carriage being movable to its initial position.

30 3. In a barrel making machine a former, a carriage adjacent thereto, and means upon the carriage for engaging one edge of each of a succession of staves and for supporting the other edge of an adjacent stave above 45 the first mentioned edge.

35 4. In a barrel making machine a former, a carriage for feeding stock thereto, means on the carriage for supporting hoop strips longitudinally upon the carriage, and means upon the carriage for engaging one edge of each of a succession of staves and for supporting the other edge of an adjacent stave above 50 the first mentioned edge, said staves being supported transversely above the hoop strips.

40 5. In a barrel making machine a former, a carriage for feeding stock thereto, means for supporting hoop strips longitudinally of the carriage, means for engaging one edge of each of a succession of staves and for supporting the other edge of an adjacent stave above 55 the first mentioned edge, said staves being supported transversely of the carriage and above the hoops, and separate means 60 cooperating with the former and carriage

for attaching the ends of each hoop strip to the former and carriage respectively.

6. In a barrel making machine a former, a carriage, means cooperating with the former and carriage for engaging the respective ends of a hoop strip, means on the carriage for engaging one edge of each of a succession of staves and for supporting the other edge of an adjacent stave above the first mentioned edge, said staves being supported transversely above the hoop strips and upon the carriage, and means for actuating the former to wrap the hoop strip upon the former and bind the staves between the strip and the former.

7. In a barrel making machine the combination with a former and a carriage, of means cooperating with the former and carriage for engaging opposite ends respectively of a hoop strip, means on the carriage for engaging one edge of each of a succession of staves and for supporting the other edge of an adjacent stave above the first mentioned edge, said staves being supported transversely above the hoop strip, means for rotating the former intermittently to pull through the hoop strip upon the carriage to feed the staves between the hoop strip and the former, and means for automatically fastening together the hoop strip and staves during the pauses in the movement of the former.

8. In a barrel making machine the combination with a former, means for feeding stock thereto, and means cooperating with the former for gripping the stock, of drive mechanism including clutch members, means for shifting the clutch members to operate the former in either direction, and means actuated by said mechanism for automatically shifting the clutch members to stop the rotation of the former in either direction at predetermined points.

9. In a barrel making machine the combination with a former, of drive mechanism including clutch members, means for shifting the clutch members to rotate the former in either direction, and means actuated by said drive mechanism for stopping the rotation of the former when it reaches a predetermined point.

10. In a barrel making machine the combination with a former, of drive mechanism including clutch members, means for shifting the clutch members to rotate the former in either direction, and means actuated by said drive mechanism for stopping the rotation of the former when it reaches a predetermined point, said means including a gear, cam blocks adjustable annularly upon the gear, a clutch shifting lever, and separate means movable with the lever for actuation by the respective blocks.

11. In a barrel making machine the combination with a former, of drive mechanism

including clutch members, a lever for shifting the clutch members to rotate the former in either direction, and means actuated by said mechanism for stopping the rotation of the former when it reaches a predetermined point, said means including a gear, cam blocks adjustable annularly upon opposite sides of the gear, and separate means movable with the lever and extending to opposite sides of the gear for actuation by the respective cam blocks.

12. In a barrel making machine the combination with a former, of drive mechanism including clutch members, a lever for shifting the clutch members to rotate the former in either direction, and means actuated by said mechanism for stopping the rotation of the former when it reaches a predetermined point, said means including a gear, cam blocks adjustable annularly upon opposite sides of the gear, a slide extending across the gear, a finger adjustable on the slide for engagement by one of the cam blocks, a pin movable in the slide for engagement by the other cam block, and means on the lever for disengaging the pin from its cam block.

13. In a barrel making machine the combination with a former having grooved sections for engagement with a liner hoop, of a shiftable cross head, a head mounted for rotation thereon and having means to engage a liner hoop, means for holding a barrel head to the rotatable head, means for fastening the cross head in position to clamp a barrel head between the former and the rotatable head, means for feeding stock to the former, means for intermittently rotating the former to bend the stock there around, and means operating during pauses in the rotation of the former for nailing the stock together and to the liner hoops.

14. In a barrel making machine the combination with a former having sections for engagement with a liner hoop, of a head mounted for rotation adapted to support a liner hoop, means for clamping a barrel head between the rotatable head and said sections, the heads and sections being revolute together, means for intermittently rotating the former and heads, means for feeding stock to the former to surround the former, and means for nailing through the stock and

into the liner hoops during pauses in the rotation of the former.

15. In a barrel making machine the combination with a former and means for feeding stock thereto, of a shiftable cross head, a head mounted for rotation on the cross head, means slidably mounted on the rotatable head for engaging and supporting a barrel head, and means movably mounted on the rotatable head for simultaneously shifting the slidable means to release an engaged barrel head.

16. In a barrel making machine the combination with a former mounted for rotation, of means for clamping a barrel head thereto, including a rotatable head, means slidably engaging the rotatable head for engaging and supporting a barrel head, means for securing the rotatable head in position to clamp an engaged barrel head against the former, a cam ring, and means operated by the cam ring for disengaging the slidable means from the barrel head.

17. In a barrel making machine the combination with a former having means to engage a liner hoop, of a rotatable head having means to engage a liner hoop, means for supporting the rotatable head in position to clamp a barrel head against the former and between said liner hoops.

18. In a barrel making machine the combination with a former having means to engage a liner hoop, of a rotatable head having means to engage a liner hoop, means for supporting the rotatable head in position to clamp a barrel head against the former, means cooperating with the former for gripping one end of a hoop strip, means for intermittently rotating the former to wrap the hoop strip therearound to bind staves upon the former, and means for nailing through the hoop strip and staves and into the liner hoops during pauses in the movement of the former.

In testimony that I claim the foregoing as my own, I have hereto affixed my signature in the presence of two witnesses.

JOSEPH L. WALKER.
